CLAIM

The ornamental design for a scraper handle, as shown and described.

DESCRIPTION

FIG. 1 is a top plan view of the scraper handle showing our new design;

FIG. 2 is a side elevation view of one side of the scraper handle, the opposite side being a mirror image;

FIG. 3 is a bottom plan view thereof;

FIG. 4 is an end elevation view from the left end of FIG. 2; and,

FIG. 5 is an end elevation view from the right end of FIG. 2.
